ATTYS.

UNITED STATES PATENT OFFICE.

ARTHUR HUGO MÜLLER, OF BLANKENESE, NEAR HAMBURG, GERMANY.

SWITCH DEVICE FOR OVERHEAD TRACKS.

Application filed September 4, 1924. Serial No. 735,933.

To all whom it may concern:

Be it known that I, ARTHUR HUGO MÜLLER, citizen of Germany, residing at Blankenese, near Hamburg, Germany, Bismarckstrasse 9, have invented certain new and useful Improvements in a Switch Device for Overhead Tracks, of which the following is a specification.

In plants for towing ships or vessels on a water way by a trolley running along an overhead track it is of advantage to provide means to enable the trolley to pass directly on branches of the chain-like track.

By these means the landing of the vessels at the banks and the passing and overtaking of other ships at suitable overtaking places is essentially facilitated.

The object of the present invention is to provide means of this kind.

With this object in view one part of the main track forming a switch tongue is resting with its free end slidably on a cross beam suspended from a system of carrier wires fastened to poles erected on the banks of the water way. By thus sliding the said switch tongue, which is pivotally connected with its other end to the main track, to one side or the other the first named free end of the tongue coincides with either of the prolongation of the main track or with the branch track.

At the same time the electric conductor, which is also suspended from the carrier wire system and which is adapted to be disconnected next to the free end of the switch tongue, is also slid to one side together with the tongue so as to make or break contact with either the main conductor or the branch conductor as the case may be. In order to save special attendants for the switch device the latter can be operated or set from the ship in passing by a suitable shunting device.

Fig. 1 is a diagrammatical view of two main tracks and two branch tracks.

Fig. 2 is a similar view drawn to a larger scale of the switch device.

Fig. 3 is a section drawn to the line 3—3 of Fig. 2, and

Fig. 4 is a section drawn to the line 4—4 of Fig. 2.

In the construction shown it is taken that the plant for towing vessels has a main track I for river-up and a main track II for river-down. The corresponding branch tracks I'

and II' can be shunted to the main tracks by the switch devices *a* and *a'* and the double switch device or crossing *a*². The switch proper *a* or *a'* is constituted by a tongue, which is pivotally connected at *b* or *b'* respectively with the main track I or II respectively. The free end of the tongue *a* rests on one of a series of cross beams *c*, which by the aid of rods *d* are suspended from a carrier wire system *e* secured in any suitable manner on the bank of the water way. By shifting the tongue *a* or *a'* respectively it can be made to coincide either with the main track I or the branch I' (or II and II' respectively). Antifriction rollers *g* may be provided running on top of the beams *c* for supporting the free end of the tongue *a*. For operating the switch device shunting devices *f* of any known construction can be provided, which at a suitable distance are suspended on the wire system and operated by the ship or vessel passing by. The position of the switch tongues can be indicated by signals *g'* as is usual in railway plants. The shunting of the crossing or double switch tongue *a*² is carried out in the same manner as of the switch tongues *a* or *a'*, the point of crossing being the pivot point of the double tongue, and the two ends are resting slidably on cross beams *c* in a similar manner as is described with regard to the single switch tongue. The shunting of the double switch may be carried out at the same time as the single switch tongue.

It remains to be explained that the electric conductors *h*, which are also suspended from the cross beams *c* and which are adapted to be interrupted next to the free ends of the switch tongues, can be shunted in similar manner as the switch tongue *a*, *a'* and *a*², so as to maintain the necessary electric circuit for the passing of the ships from the main track to the branch track or vice versa.

I claim:

1. A switch device for overhead tracks comprising a main track and a branch track, a wire system from which the said tracks are suspended, a cross beam also suspended from said wire system, a switch tongue forming part of the main track and pivoted thereto with one end, the other end of said switch tongue slidably resting on the cross beam, to coincide either with the main track or the branch track.

2. A switch device for overhead tracks comprising two main tracks and two branch tracks, a wire system from which the said tracks are suspended, two cross beams also suspended from said wire system, a pivotally mounted double switch tongue forming a crossing switch and part of one of the main tracks where it crosses the branch track of the other main track, the ends of the said double switch tongue slidably resting on said cross-beams to coincide either with the said main track or with the said branch track.
3. A switch device for overhead tracks comprising a main track and a branch track, a wire system from which the said tracks are

suspended, a cross beam and a longitudinal electric main conductor, both suspended from said wire system, a branch conductor, the main conductor being adapted to be 20 opened in the vertical plane of the said cross-beam, a switch tongue forming part of the main track and pivoted thereto with one end, the other end of said switch tongue 25 slidably resting on the cross beam, to coincide either with the main track or the branch track that part of the main conductor adjacent the switch tongue being connected therewith so as to be adapted to make contact with the branch conductor, when the branch 30 track is shunted on.

ARTHUR HUGO MÜLLER.
